F. H. MICHAELIS

WALL CONSTRUCTION FOR BATHROOMS

Filed June 6, 1927

UNITED STATES PATENT OFFICE.

FREDERICK H. MICHAELIS, OF KANSAS CITY, MISSOURI.

WALL CONSTRUCTION FOR BATHROOMS.

Application filed June 6, 1927. Serial No. 196,753.

This invention relates to wall construction and is designed more especially as a substitute for wall tiling in bath rooms and the like. Walls composed in whole or in part of the customary glazed tiling are expensive, not only because of the relatively high cost of such tile, but because very skilled labor is required to lay the tile. Furthermore when repairs are necessary, skilled labor is necessary and the cost for repairs is correspondingly high.

My object is to produce a wall construction which is of as attractive appearance as a wall composed of glazed tile or the like, and which is of greater strength and durability. A further object is to produce a metal shell wall construction possessing the desirable attributes above mentioned and which is much more economical in first cost and installation than brick tiling, can be installed or erected in a fraction of the time required to lay brick tiling, and may have an enameled face which may be as readily washed and cleaned as glazed brick tiling.

With the above objects in view, the invention consists in certain novel and useful features of construction and combinations of parts as hereinafter described and claimed; and in order that it may be fully understood, reference is to be had to the accompanying drawing, in which:—

Figure 1 is an inner face view of a fragment of a wall construction embodying the invention and simulating brick tiling in appearance.

Figure 2 is an end view of the same.

Figure 3 is an enlarged vertical section taken on the line III—III of Figure 1, the main or tiling plate member being broken away at two points to foreshorten it vertically.

Figure 4 is a perspective view on a scale intermediate that of the preceding figures, and showing the main or tiling plate member shortened vertically by breaking it away in two places, the figure also showing the base-board member, the tiling member and the rail member spaced apart to indicate more clearly the method of their assembly.

Figure 5 is a fragmentary view showing the rail and the main or tiling plate member assembled operatively but with a border strip interposed between them.

Referring now to the drawing in detail, 6 indicates a floor support or joist construction, 7 a wall construction which in many cases will include lathing of the expanded metal type, illustrated in the conventional manner for wire netting as at 8. Any other means to which cement will adhere may be used in lieu of lathing.

The wall facing proper, comprises three metal members in superposed relation, namely, a floor board member 9, a main or tile member 10, and a head rail member 11. The floor board member is in the form of a metal strip disposed vertically around the room in the same manner as an ordinary floor board, except that the strip is of angular form, so that when its top flange or arm 12 is fitted against the lathing there is provided between the latter and the body portion of the strip a vertical chamber 13. The floor board member is preferably continuous except for doorway intersections or the like (not shown), and at its lower edge it is provided with a flange 14 through which it is nailed or otherwise fastened to the floor construction of the room projecting from the outer edge of the flange or arm 12, which is horizontal by preference, there is provided an angular extension or upwardly-projecting flange 15, which fits against and is nailed or otherwise fastened to the wall construction.

The flange 14 is adapted to underlie the flooring indicated at 16, and at the junction with the flooring the floor board member is curved to extend downwardly and inwardly as at 17 to the plane of the upper surface of the flooring and thus form a round corner and avoid an angle at such point in which dust and the like may settle to make cleaning more difficult and laborious. The round corner furthermore adds to the attractiveness of the room, and in this connection it may be stated that at each corner of the room there will be corner strips abutting strips (not shown) but preferably of rounded form so as to provide rounded wall corners for the room, these rounded wall corners not being illustrated as in all other respects they are identical with the strips 9. The top flange or arm of each floor board member is provided with a series of openings 18 produced by stamping out of the arm a corresponding series of depending tongues 19, which tongues are spaced from

the body of the floor board member and the adjacent wall construction, and the said arm 12 is furthermore provided with a plurality of elongated openings or slots 20 adjacent the 5 flange 15.

The member 10 which is the main or wall member, is also of sheet metal and is preferably of channel form, and is arranged with its lower flange or arm 21 fitted flatly upon 10 the flange or arm 12 of the floor board member, the upper flange or arm 22 of member 10 abutting the wall construction and being provided at its outer margin with an upwardly-projecting flange 23 nailed or otherwise fastened 15 to the wall construction. At the outer edge of the flange or arm 21 are formed a series of depending tongues 24 extending down through the elongated openings or slots 20 of arm 12 of the floor board member, 20 whereby the lower portion of the member 10 is interlocked to the underlying member 9 as regards movement in every direction except upward movement, which movement is prevented by the nailing or other fastening 25 of flange 23 to the wall construction, as explained. The flange or arm 21 is provided with openings 25 registering with openings 18 of flange or arm 12 of the floor board member, and said openings 25 are provided 30 by stamping out of flange or arm 21, the upwardly-projecting tongues 26, which like tongues 19 are intermediate the space between the body portion of channel plate member 10 and the wall construction. The upper 35 flange or arm 22 of the member 10 is also provided with a series of openings 27 corresponding to openings 25, and produced by stamping out of said flange or arm the depending tongues 28, and the flange or arm 40 22 adjacent its upwardly-projecting flange 23 is provided with a series of elongated opening or slots 29.

The rail member 11 is also preferably of channel form, but by preference, the channel is deeper than the channel of member 10, so that said rail member shall overhang at the inner side or face of member 10, and for ornamental effect the lower inner corner of the rail member 11 is of compound curve 45 form, in end view as at 30. The lower arm 31 of member 11 is provided with openings 32 registering with openings 27, and produced by stamping out of arm 31, upwardly-projecting tongues 33. The arm 31 is also 50 provided at its outer margin with depending tongues 34 extending through the openings or slots 29 of flange or arm 22 and interlocking the rail member with member 10 as regards movement in all directions except 55 vertically upward. The upper arm of the rail member 11 is provided with a flange 35 fitting against and nailed to the wall construction, and said upper arm of the rail member is provided with a suitable number 60 of openings 36 produced by stamping down- 65

wardly out of said arm, the tongues 37. From the foregoing it will be apparent that there is communication established vertically between the spaces provided between the wall structure and the superposed members respectively, so that when cementitious material in semi-fluid condition is poured in at the top in sufficient quantity it will fill the entire void and constitute a solid backing for the sheet metal members and a means, 70 through its adherence to the metal or equivalent lathing of the wall structure, of permanently anchoring the sheet metal members in position, this union of course being made more dependable by reason of the embedment of the various internal tongues of the members, in the cement, a later reference herein making more specific mention of the preferred course followed in applying the cementitious material, and to an alternate 75 method of applying such material.

If it is desired that the wall member shall appear as tiling, it will be formed on its inner face with intersecting grooves. To simulate conventional tiling, such grooves are formed 80 as horizontal and vertical intersecting grooves 38 and 39, which grooves can be filled or pointed with mortar or the like, to give a more realistic imitation of individually laid tiles, and it is also desirable at the 85 joints between the members 9 and 10, and 10 and 11, to provide joints which conform in appearance to the joints 38, and this is accomplished by recessing the lower inner corners 90 of the members 10 and 11, as indicated at 40 100 and 41 respectively.

It will be apparent of course that the inner faces of the various members may be enameled to provide a durable gloss finish in white or any other color or combination of colors, 105 to still further add to the realistic tiling effect produced on the mind of the beholder and to provide a finish which can be readily and easily cleaned. When the members of the wall have been assembled together as explained, the wall can be made solid and substantial after first closing the space at the bottom of the floor board member with lathing 42 or otherwise, by pouring a semi-liquid cement or material of a cementitious nature 110 through the openings 36 of the rail member, this material passing down through the various registering openings mentioned until the entire space from the floor to the top of the rail member is a solid mass 43 which becomes 115 monolithic when set, and by adherence to the wall construction, and by embedment of the various tongues mentioned, cooperates with the fastening devices hereinbefore mentioned, in securing the metal wall members permanently and rigidly in position. It will be understood of course that if the semi-liquid material is not of a too quick-setting character, it can be placed in each member after 120 the same has been secured in position, in- 125

stead of being introduced only at the top of the rail member, as hereinbefore suggested. After the installation described has been effected, the walls may be plastered above the 5 rail member, and cover and hide from view the flange 35 by which the rail member is nailed or otherwise fastened to the wall construction.

Where it is desired to provide an insert 10 border at the bottom of the rail member, the latter will be spaced above the member 9, but still interlocked therewith by overlapping the flange 23 with the depending tongues 34 and nailing or otherwise fastening both to the 15 wall construction. This space or channel can then be closed by a border strip or bar 44 of ornamental appearance or color contrasting with that of the adjacent wall members, the strip or bar being cemented or otherwise secured 20 in position.

From the above description, it will be apparent that while I have described and illustrated the preferred embodiment of the invention, it is to be understood that I reserve 25 the right to make all changes which properly fall within the spirit and scope of the appended claims.

I claim:

1. In a room wall, an upright plate member secured to the floor construction and spaced from the wall construction, and provided at its upper edge with an arm extending outwardly and secured to the wall construction and provided with a plurality of 30 openings, a plate superimposed on the first-named plate and spaced from the wall construction and provided at its lower edge with an outwardly-projecting arm fitting flatwise on and interlocked with the outwardly-projecting arm of the first-named plate and provided with openings registering with the openings of said arm of the latter; said superimposed plate having at its upper end, an outwardly-projecting arm fastened to the 35 wall construction and provided with one or more openings through which cementitious material may be introduced to fill the spaces between the wall construction and said plates and the openings in the arms of the latter, one of the plates at its junction with the other plate and in the plane of the body portion of the plates being offset to provide a horizontal joint opening through the inner face of the wall surface formed by said plates and susceptible of being pointed with cementitious material; said superimposed plate being provided over its inner face, with intersecting grooves to be filled or pointed with cementitious material to simulate tiling of predetermined form and size.

2. In a room wall, an upright plate member secured to the floor construction and spaced from the wall construction, and provided at its upper edge with an arm extending outwardly and secured to the wall construction and provided with a plurality of openings, a plate superimposed on the first-named plate and spaced from the wall construction and provided at its lower edge with an outwardly-projecting arm fitting flatwise on and interlocked with the outwardly-projecting arm of the first-named plate and provided with openings registering with the openings of the arm of the latter; said superimposed plate having at its upper end, an outwardly-projecting arm fastened to the wall construction and provided with one or more openings, and a channel rail plate member above the said superimposed plate member, and provided with a lower outwardly-projecting arm abutting the wall construction at its outer edge and interlocked with the said superimposed mem- 65

tion and provided with one or more openings through which cementitious material may be introduced to fill the spaces between the wall construction and said plates and the registering openings in the arms of the latter, one of the plates at its junction with the other and in the plane of the body portions of both being offset to provide a horizontal joint opening through the inner face of the wall surface formed by said plates and susceptible of being pointed with cementitious material. 70

3. In a room wall, an upright plate member secured to the floor construction and spaced from the wall construction, and provided at its upper end with an arm extending outwardly and secured to the wall construction and provided with a plurality of openings, a plate superimposed on the first-named plate and spaced from the wall construction and provided at its lower edge with an outwardly-projecting arm fitting flatwise on and interlocked with the outwardly-projecting arm of the first-named plate and provided with openings registering with the openings of the arm of the latter; said superimposed plate having at its upper end, an outwardly-projecting arm fastened to the wall construction and provided with one or more openings through which cementitious material may be introduced to fill the spaces between the wall construction and said plates and the registering openings in the arms of the latter, one of the plates at its junction with the other plate and in the plane of the body portion of the plates being offset to provide a horizontal joint opening through the inner face of the wall surface formed by said plates and susceptible of being pointed with cementitious material; said superimposed plate being provided over its inner face, with intersecting grooves to be filled or pointed with cementitious material to simulate tiling of predetermined form and size. 90

4. In a room wall, an upright plate member secured to the floor construction and spaced from the wall construction, and provided at its upper end with an arm extending outwardly and secured to the wall construction and provided with a plurality of openings, a plate superimposed on the first-named plate and spaced from the wall construction and provided at its lower edge with an outwardly-projecting arm fitting flatwise on and interlocked with the outwardly-projecting arm of the first-named plate and provided with openings registering with the openings of the arm of the latter; said superimposed plate having at its upper end, an outwardly-projecting arm fastened to the wall construction and provided with one or more openings, and a channel rail plate member above the said superimposed plate member, and provided with a lower outwardly-projecting arm abutting the wall construction at its outer edge and interlocked with the said superimposed mem- 115

- ber, and provided with one or more openings, and provided also at its upper edge with an outwardly-projecting arm provided at its outer edge with an upwardly-projecting 5 flange secured to the wall construction, said upper arm having one or more openings through which cementitious material may be introduced for filling the said rail member and the underlying members by passage 10 through the openings of the respective arms of said members.

5. In a room wall having an upright plate member secured to the floor construction and spaced from the wall construction, an arm 15 extending outwardly from the plate and secured to the wall construction, a second upright plate member superimposed on the first-named plate and interlocked therewith, and provided at its upper end with an outwardly-projecting arm secured to the wall construction, the said outwardly-projecting arms of the members having openings through which a cementitious material may be introduced 20 into and fill the spaces between the upright plates and the wall construction, the provision in the room wall characterized thus of tongues rigid with the said plates and standing between the latter and the wall construction.

25 6. In a room wall characterized as in claim 30 2, the provision of tongues projecting from the arms of said plates marginally of the openings of the arms and standing in planes intersecting that of said arms.

35 7. In a room wall, plates in vertical superposed edgewise abutting relation, the bottom plate having a lower portion curved downward and inward and terminating at its inner margin in a depending flange secured to 40 the floor construction, said plate also at its upper edge, having a perforated arm projecting outwardly and secured to the wall construction and the plate upon the bottom plate having perforated arms projecting outwardly, the lower arm resting upon and interlocked 45 with the arm of the bottom plate with the perforations of the arms in register, and the upper arm of the superposed plate being secured to the wall construction.

50 8. In a room wall characterized as in claim 7, the provision of tongues rigid with said arms and standing between the respective plates and the wall construction.

55 9. In a room wall, an upright plate member secured upon the floor construction and spaced from the wall construction and provided at its upper edge with an outwardly-projecting arm abutting and secured to the wall construction, a channel plate member superimposed sidewise on the said arm of the 60 first-named member and forming a continuation of the inner surface of the latter, the upper arm of the channel member being secured to the wall construction in a plane above

that of the upper edge of said member, the 65 said abutting arms of the plates having a plurality of registering openings, and one of the abutting arms having a plurality of slots adjacent the wall construction and the other arm a plurality of tongues extending through said 70 slots and interlocking the plates together as regards lateral and endwise or longitudinal movement.

10. In a room wall, an upright plate member secured upon the floor construction and spaced from the wall construction, and provided at its upper edge with an outwardly-projecting arm abutting and secured to the wall construction, a channel plate superimposed sidewise on the said arm of the first-named plate and forming a continuation of the inner surface of the latter, the upper arm of the channel member being secured to the wall construction, and the said abutting arms of the plates having a plurality of registering 75 openings, one of the abutting arms having a plurality of slots adjacent the wall construction and the other arm a plurality of tongues extending through said slots and interlocking the plates together as regards lateral and endwise or longitudinal movement, and a channel head rail member secured in sidewise position to the wall construction above the first-named channel member and interlocked with the latter and provided in its lower horizontal 80 arms with openings registering with the openings in the upper arm of the first-named channel member, and with openings in its upper arm, and a border strip interposed between the said channel member and channel head rail member, with its inner face flush with the inner face of the former.

85 11. The combination with a room wall having an inner facing to which cementitious material will adhere, of a vertical metal facing for the interior face of said wall and spaced inwardly therefrom, and comprising superimposed channel members arranged horizontally with the bottom flange of one resting 90 flatly on the top flange of the other, the lower plate member being provided at its upper end with a flange extension directly engaging the inner facing of and fastened to the wall structure, and the upper member being provided at its lower edge with an arm depending 95 through the upper flange of the underlying member and interlocking the members together as regards independent movement of the upper member inward of the lower member; said superimposed members having registering openings providing continuity of the space between them and the wall structure from the bottom of the lower to the top of the upper member.

100 12. The combination with a wall structure of a room, of an interior wall facing, comprising sheet metal channel members extending

ing horizontally and standing edgewise in superimposed relation, with the lower flange of the upper member resting flatly on the upper flange of the lower member; the upper flange of the lower member having an extension directly engaging and fastened to the wall structure, and the abutting flanges of

the members having registering openings and bearing an interlocked relation limiting movement of the lower end of the upper member in 10 a direction away from the wall structure or longitudinal thereof.

In testimony whereof I affix my signature.

FREDERICK H. MICHAELIS.
